UNITED STATES PATENT OFFICE.

JULIUS ENGELBRECHT, OF BOONE, COLORADO.

SCRAPER.

1,355,134.

Specification of Letters Patent. Patented Oct. 12, 1920.

Application filed March 5, 1919. Serial No. 280,831.

To all whom it may concern:

Be it known that I, JULIUS ENGELBRECHT, a citizen of the United States, residing at Boone, in the county of Pueblo and State of Colorado, have invented a new and useful Scraper, of which the following is a specification.

It is the object of this invention to provide a simple device, adapted to be attached to a ditcher-body shaped to throw the dirt in opposite directions, the device being so constructed that when it is attached to the body, the body will throw the dirt laterally in one direction only.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in side elevation, a ditcher-body whereunto the device forming the subject matter of this application has been attached; Fig. 2 is an elevation showing the opposite side of the structure from that delineated in Fig. 1; and Fig. 3 is a top plan.

The numeral 1 designates a ditcher-body adapted to constitute a part of a ditching machine or like mechanism. Since the ditcher-body may be of any desired sort, it has been reduced to the simplest possible form in the drawings, and is depicted in the form of a mere block including mold boards 2 and 3 adapted to pass the dirt laterally in opposite directions. For convenience in describing the way in which the attachment forming the subject matter of this application may be reversed, the sides of the body are denoted respectively by numerals 4 and 5. The body 1 may include a point 6 defined by shares 7, the shares 7 approaching the horizontal more closely than do the mold boards 2 and 3.

In carrying out the invention there is provided a deflector 8, preferably in the form of a plate, provided at its upper and lower edges with outwardly extended diverging flanges 9. The deflector 8 terminates in a

reduced end 10, merging into a tongue 11, the tongue 11 being disposed approximately parallel to the deflector 8 and to the rear thereof. A support 12, preferably in the form of a strip, is disposed at an acute angle to the deflector 8 and projects rearwardly therefrom, the support being supplied at its forward end with an acutely disposed inwardly projecting extension 14 attached by a securing device 15 to the rear surface of the deflector 8.

In the drawings, the support 12 extends along the side 4 of the body 1 and is attached thereto by securing elements 16. The tongue 11 rests against the mold board 3 and is attached thereto by a securing device 17. The construction is such that the plate or deflector 8 is held in approximately parallelism to the mold board 3.

If desired, the deflector 8 and attendant parts may be turned upside down, the support 12 being attached to the side 5 of the mold board, the tongue 11 being attached to the mold board 2.

It is obvious that the device forming the subject matter of this application may be reversed, so as to throw, to opposite sides, at the will of an operator, dirt which, otherwise, would be cast laterally in opposite directions, at the same time, by the elements 2—3 and 7—7.

Referring to Fig. 2, it will be observed that when the attachment is assembled with the body 1, the lower flange 9 of the deflector 8 rests upon one of the shares 7, to aid in steadyng and sustaining the deflector.

Having thus described the invention, what I claim is:—

1. The combination with a ditcher-body having diverging mold boards, of a deflector disposed approximately parallel to one mold board, the deflector having rearwardly extended parts attached respectively to said mold board and to one side of the body, the deflector being reversible to dispose the deflector in approximate parallelism with respect to the other mold board, and to permit said parts to be attached, respectively, to the first specified mold board and to the other side of the body.
2. An attachment of the class described

105

comprising a plate like deflector provided at one end with an end member disposed at an acute angle to the deflector, the end member terminating in a tongue located approximately parallel to the deflector; and a support disposed at an acute angle to the deflector and in approximate parallelism to

said end member, the forward extremity of the support being attached to the deflector.

JULIUS ENGELBRECHT.
